UNITED STATES PATENT OFFICE

149,029

DESIGN FOR A TOILET KIT

Clyde Sims, Dallas, Tex.

Application March 28, 1946, Serial No. 128,029

Term of patent 14 years

(Cl. D86—10)

To all whom it may concern:

Be it known that I, Clyde Sims, a citizen of the United States, residing at Dallas, in the county of Dallas and State of Texas, have invented a new, original, and ornamental Design for a Toilet Kit, of which the following is a specification, reference being had to the accompanying drawing, forming part thereof.

I claim:

The ornamental design for a toilet kit, as shown.

CLYDE SIMS.
